(57) **CLAIM**

The ornamental design for a mandrel, as shown and described.

DESCRIPTION

FIG. 1 is a perspective view of a mandrel showing our new design.

FIG. 2 is a first side view of the mandrel of FIG. 1.

FIG. 3 is a second side view of the mandrel of FIG. 1.

FIG. 4 is a third side view of the mandrel of FIG. 1.

FIG. 5 is a fourth side view of the mandrel of FIG. 1.

FIG. 6 is a front end view of the mandrel of FIG. 1; and, FIG. 7 is a rear end view of the mandrel of FIG. 1.

Portions of the mandrel shown in dash-dot lines form no part of the claimed design. Portions of the mandrel shown in dot-dash lines indicate boundaries of the claimed portions and form no part of the claimed design.

1 Claim, 4 Drawing Sheets
